UNITED STATES PATENT OFFICE.

EDWARD J. MCKOWN, OF ROCHESTER, NEW YORK, ASSIGNOR TO WILLIAM H. VICK, OF SAME PLACE.

LAMP.

SPECIFICATION forming part of Letters Patent No. 352,252, dated November 9, 1886.

Application filed May 6, 1886. Serial No. 201,367. (No model.)

To all whom it may concern:

Be it known that I, EDWARD J. MCKOWN, of the city of Rochester, in the county of Monroe and State of New York, have invented a certain new and useful Improvement in Lamps; and I do hereby declare that the following is a full, clear, and exact description of the same, reference being had to the drawings accompanying this application.

10 My improvement relates to Argand lamps; and the object is to secure better combustion by the use of a burner of peculiar construction, with an interior attachment having a main and auxiliary button, one located inside 15 the other, and a device for directing the currents of air to the buttons, all as hereinafter described.

In the drawings, Figure 1 is a central vertical section of a lamp showing my improvement. Fig. 2 is a perspective view of the button attachment. Fig. 3 is an enlarged central section of the device for operating the screw of the wick-raiser. Fig. 4 is a plan view of the wick-raiser and a cross-section of the screw-shaft.

25 A indicates the base of the lamp. B is the hollow standard. C is the central air-tube, and D is the oil fount or body of the lamp, all of ordinary construction. The base or the standard is perforated, as shown at a, to admit air to the interior, and a perforated plate, b, is used at the bottom of the standard to break the force of the currents as they pass upward through the air-tube.

30 My improvement is as follows: E is the burner, which is fitted in the top of the lamp, as usual. This burner is in the form of an inverted frustum of a cone, and has perforated sides c c to admit outside air to the burner.

35 G is an exterior cone rising from the flat top of the burner and surrounding the wick-tube H. A space is left at the base of this cone and between it and the chimney I, and the air that enters through the perforated sides c c of the burner passes up through holes d into this space and into the blaze.

40 K is an attachment that fits loosely into the top of the open central air-tube, C. It consists of a short section of tube, f, of smaller diameter than the air-tube, and a series of ra-

dial wings, g g, at the bottom, which are of sufficient diameter to fill the air-tube. At the top of the tube f is the main button h, which consists of a rim, forming part of the tube f, turned over in curved form, as shown. The sides of 55 the button incline outward from the body of the tube f, and the rim is turned over sufficiently to give a downward turn to the air that follows up the inclined sides, and thus force it out into the blaze.

60 L is an auxiliary button located on a stud inside of and a little below the top of the main button, with an annular space left between its edges and the inside of the tube f, and the office of this supplementary button is 65 to also deflect the air outward over the top of the main button and into the blaze at a higher level than the currents under the main button.

The attachment K is inserted loosely in the upper end of the central air-tube, C, and strikes 70 a stop at the bottom, which gages its position. The air passing up the central tube is caught by the radial wings g g and divided into separate columns, which insures equal distribution on all sides. At the top of the wings a 75 portion of the air passes up inside and a portion outside of the short tube f. The portion that goes up outside passes under the main button h and is deflected outward and downward into the blaze, while that which goes inside the tube passes up under the supplementary button L and is deflected outward into the blaze above the main button and at a higher level, as before described. At the same time the air that passes up the exterior cone, G, enters 80 the blaze just at the point of ignition, while the air that passes up outside of said exterior cone, and between it and the chimney, enters the blaze at a higher level outside. By 85 the means above described many currents of air are brought in contact with the blaze at different points, which produces perfect combustion and a white light.

90 M is a circular band that encircles the wick N around the central air-tube, C, and serves 95 as a raiser. The band may be provided with teeth that hold in the wick. The band has a stem, k, that projects outward, and is provided with a socket, k', at its outer end to receive the screw.

P is the screw. It passes through the socket k' and extends up through the top of the lamp-body.

R is a filling-cap that screws into a nozzle 5 at the top of the lamp. The cap is hollow, and in it is seated a hub, l, which turns freely and is provided with a square open-ended socket, through which the upper square end of the screw-shaft passes loosely. The hub ex-10 tends up through the top of the cap, and is provided with a thumb-piece, m, by which it is turned. By unscrewing the cap R it, together with the hub, can be slipped off free from the shaft, and the lamp can then be filled through 15 the opening. When the cap is in place, motion can be imparted to the screw by simply turning the hub in the cap, thus moving the wick up or down on the central tube, C.

Having described my invention, what I claim 20 as new, and desire to secure by Letters Patent, is—

1. In an Argand lamp, the combination, with the central air-tube, of the attachment K, consisting of the inner tube, f, the radial 25 wings g g, the main button h, at the top of the tube, with its outer edge curved outward, and

the auxiliary button L inside the main button, as shown and described, and for the purpose specified.

2. In an Argand lamp, the combination, 30 with the central air-tube, of the attachment K, consisting of the inner tube, f, radial wings g g, main button h and auxiliary button L, and the exterior cone, G, surrounding the wick-tube, as shown and described, and for the pur-35 pose specified.

3. The combination, with a central-draft lamp, of the wick-raiser M, and screw P, and the hollow filling-cap R, provided with an interior socket-piece, l, which is capable of turning, and through which the upper square end of the screw passes loosely, the screw receiving motion with the socket-piece as it is turned, as set forth.

In witness whereof I have hereunto signed 45 my name in the presence of two subscribing witnesses.

E. J. McKOWN.
